UNITED STATES PATENT OFFICE.

VERDA MITCHELL, OF ZAPATA, TEXAS.

DESIGN FOR A MOTOR VEHICLE.

60,916.

Specification for Design. Patented Apr. 25, 1922.

Application filed October 4, 1919. Serial No. 328,597. Term of patent 3½ years.

To all whom it may concern:

Be it known that I, VERDA MITCHELL, a citizen of the United States, residing at Zapata, in the county of Zapata and State of Texas, have invented a new, original, and ornamental Design for a Motor Vehicle, of which the following is a specification, reference being had to the accompanying drawing, forming a part thereof.

The figure is a perspective view of a motor vehicle showing my new design.

I claim:

The ornamental design for a motor vehicle as shown.

VERDA MITCHELL.
